UNITED STATES PATENT OFFICE.

JOHN C. BARBER, OF CHICAGO, ILLINOIS.

CAR-TRUCK.

SPECIFICATION forming part of Letters Patent No. 687,471, dated November 26, 1901.

Application filed July 22, 1901. Serial No. 69,173. (No model.)

To all whom it may concern:

Be it known that I, JOHN C. BARBER, a citizen of the United States, residing at Chicago, in the county of Cook and State of Illinois, have invented certain new and useful Improvements in Car-Trucks; and I do hereby declare the following to be a full, clear, and exact description of the invention, such as will enable others skilled in the art to which it appertains to make and use the same.

My present invention relates to car-trucks, and has for its object to improve the same in point of strength, durability, and cheapness of construction; and to these ends it consists of the novel devices and combinations of devices hereinafter described, and defined in the claims.

The invention is illustrated in the accompanying drawings, wherein like characters indicate like parts throughout the several views.

Figure 1 is a view in side elevation showing a car-truck designed in accordance with my invention, some parts being shown in diagram and others removed. Fig. 2 is a plan view of the central portion of the car-truck. Fig. 3 is a transverse vertical section taken approximately on the irregular line $x^3 x^3$ of Fig. 2. Fig. 4 is a vertical section taken approximately on the line $x^4 x^4$ of Fig. 2, some parts being shown in full. Fig. 5 is a detail, principally in horizontal section, on the line $x^5 x^5$ of Fig. 4, but with some parts shown in full and others broken away; and Fig. 6 is a bottom plan view showing in detail one of the so-called "bolster-hoods" and one of the upper spring-caps.

Of the standard parts of the truck the reference-letters a a' a'' indicate, respectively, the top bar, the truss-bar, and the bottom bar of the trussed side frame, and the circles a^4 indicate the wheels, the latter of which are of course journaled in boxes, (not shown,) which will be secured in the ordinary way to the side frames of the truck. The brake-beams b are provided with ordinary shoe-equipped heads b' , which are, as is usual, suspended by links b'' , the upper ends of which are supported from the truck-bolster in a manner hereinafter to be noted. Flanged saddles or bridges c rest upon and straddle the horizontal central portions of the said side frame truss-bars a' . On the upper faces the saddles c are provided

with concave roller-seats, in which rest the rollers d . At their ends said saddles are further provided with angular vertically-projecting bosses c^2 , which, as shown, are approximately square in cross-section.

The trussed side frames of the truck are tied together by transoms afforded by angle-bars f , the horizontal flanges of which at their ends rest upon the ends of the saddles c and are provided with angular perforations, through which the bosses c^2 project with close-fitting engagement. Just inward of the angular corners of the transoms f the saddles c are provided with transverse locking ribs or shoulders c^3 , which coöperate with the bosses c^2 to lock the transoms to the said saddles against twisting movements in a horizontal plane.

The truck-columns g are preferably cast hollow, and they are of course located as struts between the upper and lower bars of the trussed side frames. At their lower ends these truck-columns are provided with angular seats, which receive and closely fit the upper ends of the bosses c^2 of the saddles c . The inner portions of the lower ends of the columns g closely fit against the vertical flanges of the transoms f , and at their lower outer portions they are provided with depending lock-flanges g' , which closely fit and overlap the outer edges of the said transoms f and the outer ends of the saddles c . Ordinary nutted column-bolts g^2 are passed through the bars of the side frames, through the truck-columns g , and through the lugs and body portions of the saddles c , as best shown in Figs. 4 and 5.

The engagement of the bosses c^2 of the saddles c with the transoms f and the columns g serves to relieve the column-bolts g^2 from the shearing strains and to rigidly lock the said parts c , f , and g against torsional strain or twisting movements in a horizontal plane. This feature of construction is very important.

The truck-bolster k is of cast construction, preferably of steel, and on its upper central portion it is provided with a convex center-bearing k' , which is cast integral therewith and is provided with clearing-grooves k^2 . The convex center-bearing with radial clearing-grooves is not herein broadly claimed, inasmuch as the same is the subject-matter of my

present application, Serial No. 62,819, filed June 3, 1901, entitled "Center-plates for car-trucks." At its ends the bolster *k* is formed with pockets *k*³, which open at the bottom thereof in vertical line with the intermediate portions of the saddles *c*. Within these pockets *k*³ shimming-blocks *k*⁴ are secured, as shown, by a nutted bolt *k*⁵. Upper spring bearing-plates *m* are held in place against the under surfaces of the shimming-blocks *k*⁴ by means of the said bolts *k*⁵.

The shimming-blocks *k*⁴ are of such size that they leave endless channels around the same within the pockets *k*³, into which channels the upper rectangular rim portions of the so-called "bolster-hoods" are telescoped, the same being rigidly secured to the said bolster by means of bolts or rivets *p*'. Each bolster-hood *p* is provided at front and rear with one of a pair of coöperating combined chafing-plates and guide-webs *p*², formed on their inner faces with vertical guide-channels *p*³.

Combined roller-caps and spring-seats *t*, formed on their under faces with suitable concave roller-seats, rest upon the rollers *d*. These caps or seats *t* are provided with vertically-projecting guide-flanges *t*', which work in the guide-channels *p*³ of the depending webs *p*² of the bolster-hoods *p*. Springs *v* rest upon the combined roller-caps and spring-seats *t* and support the spring-caps *m* and through the shimming-blocks, of course, the truck *k* and its load.

As shown, the truck-bolster *k* is provided with integrally-cast side bearing-pockets *k*⁶ and brake-beam-supporting lugs *k*⁷, to the latter of which the upper ends of the brake-beam-supporting links *b*² are connected, and thereby supported from the truck-bolster, as previously indicated.

To prevent the brake-beams from falling onto the track in case their ordinary or primary supports give way, the shoe-equipped heads *b*' are made of such size, or, otherwise stated, the transoms *f* are so located with respect to the wheels, that the said heads *b*' cannot pass between the wheels and the horizontal flanges of said transoms. By reference to Fig. 1 it will be noted that if the brake-beam should be dropped from its primary support the hub portions *b*³ of the heads *b*' would fall directly onto the horizontal flange of the adjacent transom *f*, while the shoe portions of said head would rub against the faces of the wheels. By this construction accidents which might otherwise occur are averted, and at the same time the brake-beams are so supported that in case of emergency the brakes may be set or operated with effect.

Since the brake-beams are suspended from the transversely-movable truck-bolster, they of course have a tendency to move laterally therewith. To prevent this lateral movement of the brake-beams, and thereby hold the shoes in line with the faces of the wheels, it has been the common practice to provide the brake-beams with projecting pins or stops,

which strike against the sides of the truck-wheels. This construction is very objectionable.

In accordance with one feature of my invention I provide the truck-frame with stops or projections which engage the brake-heads or other portion of the brake-beams and hold the said beams and shoes against lateral movements, so that the brake-shoes will always stand in proper line with the faces of the wheels. These stop-bars *w* are in the drawings shown as rigidly secured to the transoms *f*, with their ends projecting in position to engage the inner sides of the brake-heads *b*', and to also serve to assist in supporting a brake-beam when dropped from its primary support.

As the upper spring-caps *m* are separate from the so-called "bolster-hoods," and as both are formed separate from the bolster, said parts may be moved independently if broken or worn out. Furthermore, the said spring-plates *m* may be removed and replaced in order to substitute new shimming-blocks without removing the said hoods.

It will of course be understood that the mechanism above described is capable of considerable modification within the scope of my invention.

What I claim, and desire to secure by Letters Patent of the United States, is as follows:

1. In a car-truck, the combination with trussed side frames, of saddles provided with vertical bosses, truck-columns having seats fitting said bosses, and transoms having flanges interposed between said saddles and truck-columns, and provided with seats through which the bosses of said saddles are passed, substantially as described.

2. In a car-truck, the combination with trussed side frames, of saddles resting upon lower bars of said side frames and provided with vertical bosses, truck-columns having seats fitting said bosses, transoms with flanges interposed between said saddles and truck-columns, and with said bosses passed through perforations therein, and column-bolts passed through the bars of the side frames, through said truck-columns and through the bosses and bodies of said saddles, substantially as described.

3. In a car-truck the combination with trussed side frames, of saddles resting on the lower bars thereof and provided with vertically-projecting angular bosses, the truck-columns having seats fitting said angular bosses, and the transoms having flanges interposed between said saddles and said columns with the said angular bosses passed through angular seats in said interposed flanges, and column-bolts passed through the bars of said side frames, through said truck-columns and through the bosses and bodies of said saddles, substantially as described.

4. In a car-truck, the combination with side frames, of saddles resting on the lower bars of said side frames, separable bolster-columns,

one class of said parts having angular bosses which engage correspondingly-formed seats in the other, and transoms having flanges interposed between said saddles and columns, 5 with the said bosses passed through angular seats therein, substantially as described.

5. In a car-truck, the combination with side frames, of saddles supported by the side frames, truck-columns detachably connected 10 to said saddles, transoms having flanges interposed between said saddles and columns, angular bosses passed through angular seats in said transom-flanges and interlocking said parts against thrust or torsional strains, and 15 column-bolts passed through the bars of said side frames, through said columns and through said bosses and saddles, substantially as described.

6. In a car-truck, the combination with side 20 frames having roller-seats, of rollers on said seats, combined roller-caps and spring-seats resting on said rollers, transversely-movable truck-bolster, springs compressed between said bolster and said combined roller-caps and 25 spring-seats, and hood members detachably

secured to the ends of said bolster and provided with depending guide-webs which work vertically with respect to said combined roller-caps and spring-seats, but guiding the same for transverse movements with the 30 bolster, substantially as described.

7. In a car-truck, the combination with a laterally-movable truck-bolster having hood-seats at its ends, shimming-blocks within said hood-seats, spring-caps secured against 35 the under surface of said shimming-blocks, hoods having rectangular tops telescoping into said hood-seats and around said shimming-blocks and spring-caps, which hoods are provided with depending guide-webs, and 40 combined roller-caps and spring-seats moved laterally, by said guide-webs, substantially as described.

In testimony whereof I affix my signature in presence of two witnesses.

JOHN C. BARBER.
